COUPLER

**Edmund P. Kinne, Alliance, Ohio, assignor to
American Steel Foundries, Chicago, Ill., a cor-
poration of New Jersey**

Original application April 29, 1929, Serial No.
358,881. Divided and this application February
4, 1932, Serial No. 590,855.

10 Claims. (Cl. 213—167)

This invention pertains to coupler mechanism and more particularly to means for operating couplers from the side of a car, the present application being a division of a co-pending application Serial No. 358,881 filed April 29, 1929.

An object of this invention is to improve the operation of couplers, and more particularly standard A. R. A. type of couplers, in a manner whereby the coupler can always be operated positively and easily through the medium of the uncoupling rod.

Another object is to provide simple, reliable, efficient and inexpensive coupler operating mechanism having cooperating parts so arranged that maximum lifting force may be transmitted to the lock for facilitating operation of the coupler.

Still another object is to provide coupler mechanism which will effect a great saving in the number of parts now in use, as for instance, the elimination of slack devices between the operating rod and coupler lifter.

A further object is to provide uncoupling mechanism having lost motion provided therein to permit the return of the operating handle to an inoperative position upon release thereof but which has no substantial lost motion between the uncoupling rod and the coupler mechanism in operating the coupler to full knuckle throw position.

Still a further object is to provide coupler mechanism which eliminates the slack therein to thereby cut down the movement of the uncoupling rod handle to make it possible to reduce the length of the lifter arm at the coupler end so that an increased leverage of at least three-to-one may be obtained.

Yet a further object is to provide coupler mechanism so disposed as to reduce the height of the uncoupling rod to a position whereby the operator can exert full force to the best advantage to increase the efficiency of operation and whereby the handle is so disposed that it is removed from the horizontal position as much as possible to thereby decrease the liability of injury to the operator.

A different object is to provide coupler operating mechanism which will fulfill all requirements of service and manufacture and in which the operating handle will always seek a position such that there will be no tendency to disrupt the parts nor have any relative interference with the coupled cars or coupler parts.

With these and various other objects in view, the invention may consist of certain novel features of construction and operation, as will be

more fully described and particularly pointed out in the specification, claims and drawing appended hereto.

In the drawing, which illustrates an embodiment of the device, and wherein like reference characters are used to designate like parts—

Figure 1 is a fragmentary top plan view of a coupler operating mechanism made in accordance with the present invention;

Figure 2 is a fragmentary view in end elevation of the mechanism shown in Figure 1 of the drawing;

Figure 3 is a fragmentary view in side elevation of the uncoupling rod mechanism shown in Figure 1 of the drawing, the full lines indicating closed position, and the dotted lines illustrating knuckle throw position of certain parts of the mechanism; and

Figure 4 is a view in perspective of the fulcrum member of the present mechanism.

Referring now more in detail to the drawing, an embodiment selected to illustrate the present invention is shown in connection with a car body 2 with which is associated a striking casting 4 which is provided with suitable means for supporting a coupler 6, the coupler 6 being provided with a knuckle 8 pivoted to the coupler as by means of a pivot pin or bolt 10, the lock within the coupler 6 being operated by means of a top lifter 12.

The top portion of the coupler on one side of the lifter 12 is provided with a recess 13 formed with a plane fulcrum supporting surface 15 and oppositely disposed and spaced walls 17 and 19, the wall 17 being constituted by a rib or fin extending from adjacent the pivot pin 10 toward the rear 90 of the coupler head and tapering to merge with the surface 15 substantially opposite the lifter 12. The forward portion of this recess 13 is shallow in construction and is defined on the bottom by a supporting surface 21 which extends rearwardly 95 and merges with a stepped curved surface 23 which terminates in the lower surface 15 of the recess.

Mounted upon the coupler 6 and within the recess 13 is a fulcrum member 14 which is provided with an intermediate portion 16 adapted to seat as at 18 upon the surface 15 of the coupler and a forwardly extending portion 20 having its under surface conforming substantially to the surface portions 21 and 23, the forward end of this portion 20 being provided with an eye 22, through which the pivot pin 10 passes for securing this fulcrum member 14 to the coupler. The intermediate portion 16 is provided with laterally extending lugs or wings 25 and 27 which are

adapted to engage the walls 17 and 19, respectively, for holding said fulcrum member in place and to prevent lateral displacement, while the remaining portion of the intermediate portion 16 to the rear of the wings 25 and 27 has a laterally extending portion 29 which forms an enlarged surface for seating of this fulcrum member on the coupler head. The fulcrum member 14 is further formed with a rearwardly extending portion 24 which is provided with an elongated bearing 26 for supporting an end of an uncoupling rod 28. The bearing 26 is elongated to permit the coupler to assume various operating positions in angular relation to the operating rod 28 without causing a binding between the rod and bearing which would interfere with the easy operation of the uncoupling mechanism. Furthermore, the uncoupling rod at its inner end is permitted to move forwardly and rearwardly in the elongated bearing 26 so that the lifter 12 may be raised and lowered without binding in the opening to the lock cavity of the coupler head.

The uncoupling rod 28 is provided with a handled portion 30 and has its outer end suitably supported in a loose bearing 32 of a bracket 34 suitably secured in any desired manner to the car body 2. The uncoupling rod 28 extends inwardly from the bearing 32 and has its inner end journaled or supported in the elongated bearing 26 of the fulcrum member 14. Adjacent the fulcrum member 14, the uncoupling rod 28 is knuckled as at 36 and extends forwardly and outwardly therefrom, the outer end being formed with a loop 38 adapted to encircle the lifter 12 and beneath the enlarged head 40 with which the lifter is provided.

It will thus be seen that by moving the handle 30 upwardly in a counter-clockwise direction, as viewed in Figure 3 of the drawing, the encircling loop portion 38 of the uncoupling rod is thereby moved upwardly to engage the enlarged head 40 of the lifter 12 to thereby raise the same and move the knuckle 3 to knuckle throw position, angling of the coupler 6 horizontally being permitted by the looseness provided in the bearings 26 and 32 of the fulcrum member 14 and bracket 34, respectively.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

55 I claim:

1. In coupler mechanism, the combination of a coupler having a lifter, a knuckle, means for pivotally securing said knuckle to said coupler, said coupler being provided with a recess on the top portion thereof, a fulcrum member secured within said recess by said means, said recess being adapted to hold said member and prevent lateral movement thereof, and an operating rod supported by said member for operating said lifter.

2. In coupler mechanism, the combination of a coupler having a lifter, a knuckle, a pin pivotally securing said knuckle to said coupler, said coupler being provided with a recess on the top portion thereof and extending rearwardly from said pivot pin, a fulcrum member having a part disposed within said recess and secured to said coupler by said pivot pin, said recess being adapted to hold said member and prevent lateral move-

ment thereof, and an operating rod supported by said member for operating said lifter.

3. In coupler mechanism, the combination of a coupler having a lifter, a knuckle, a pin pivotally securing said knuckle to said coupler, said coupler being provided with a recess on the top portion thereof and extending rearwardly from said pivot pin, said recess increasing in width at the rear thereof to receive portions of a fulcrum member, a fulcrum member having a part disposed within said recess and secured to said coupler by said pivot pin, said member having laterally extending lugs engaging oppositely disposed walls of said recess to brace said member and prevent lateral displacement thereof, and an operating rod supported by said member for operating said lifter.

4. In coupler mechanism, the combination of a coupler having a lifter, a knuckle, a pin pivotally securing said knuckle to said coupler, said coupler being provided with a recess on the top portion thereof and extending rearwardly from said pivot pin, a fulcrum member having a part disposed within said recess, said member being provided with an eye at one end engaged by said pivot pin and a bearing at the other end thereof, said member having an intermediate portion seating on said coupler, said recess being adapted to hold said intermediate portion and prevent lateral movement thereof, and an operating rod supported in said bearing for operating said lifter.

5. In coupler mechanism, the combination of a coupler having a lifter, a knuckle, a pin pivotally securing said knuckle to said coupler, said coupler having a recess on the top portion thereof, said recess originating in a shallow portion adjacent said pivot pin and terminating rearwardly in a relatively deep portion forming a seat for a fulcrum member, a fulcrum member having an intermediate portion seating on said coupler and disposed in said relatively deep portion and a forwardly extending arm disposed in said shallow portion and being connected to said pivot pin, said recess being adapted to hold said intermediate portion and prevent lateral movement thereof, said member having an arm extending rearwardly from said intermediate portion and having a bearing therein, and an operating rod journaled in said bearing for operation of said lifter.

6. A fulcrum member for coupler mechanism and the like, comprising a body portion having a seating surface, lugs extending laterally of said body portion, and oppositely disposed arm portions extending from said body portion and being spaced in relation to the plane of said seating surface, one of said arms having means for securing said member to a coupler and the other of said arms having means for supporting an operating rod.

7. A fulcrum member for coupler mechanism and the like, comprising a body portion having a seating surface, and oppositely disposed arm portions extending from said body portion and being spaced in relation to the plane of said seating surface, one of said arms being provided with a bearing, and means on the other of said arms for securing said member to a coupler.

8. A fulcrum member for coupler mechanism and the like, comprising a body portion having a seating surface, lugs extending laterally of said body portion, and oppositely disposed arm portions extending from said body portion and being spaced in relation to the plane of said seating

surface, one of said arms being provided with an elongated bearing, and the other of said arms terminating in an eye for securing said member to a coupler.

- 5 9. In coupler mechanism, the combination of a coupler having a lifter, a knuckle, a pin pivotally securing said knuckle to said coupler, a fulcrum member having a part secured to said pivot pin and a part seating on said coupler, said member extending rearwardly of said pivot pin and being provided with a bearing for an operating rod, spaced stops disposed on said coupler engaging the fulcrum member in spaced relation to said pivot pin to prevent lateral movement thereof about said pivot pin, and an operating rod supported in said bearing for operating said lifter.
- 10 10 15

10. In coupler mechanism, the combination of a coupler having a lifter, a knuckle, a pin pivotally securing said knuckle to said coupler, a fulcrum member having a part secured to said pivot pin and a part seating on said coupler, said member extending rearwardly of said pivot pin and being provided with a bearing for an operating rod, means on said coupler engaging the fulcrum member in spaced relation to said pivot pin to prevent lateral movement thereof about said pivot pin, and an operating rod supported in said bearing for operating said lifter.
